(57) CLAIM

The ornamental design for bakeware, as shown and described.

DESCRIPTION

FIG. 1 is a perspective view of bakeware as seen from the top side thereof;

FIG. 2 is a perspective view of the bakeware as seen from the bottom side thereof;

FIG. 3 is a front elevational view thereof;

FIG. 4 is a rear elevational view thereof;

FIG. 5 is a first side elevational view thereof;

FIG. 6 is a second side elevational view thereof;

FIG. 7 is a top plan view thereof; and,

FIG. 8 is a bottom plan view thereof.

The broken lines shown in the drawings represent unclaimed subject matter and form no part of the claimed design.
